(57) **CLAIM**

The ornamental design for a food grater, as shown and described.

DESCRIPTION

FIG. 1 is an isometric view of a food grater in accordance with the present design;

FIG. 2 is a top plan view thereof;

FIG. 3 is a bottom plan view thereof;

FIG. 4 is a front elevation view thereof, the rear elevation view thereof is a mirror image of the front elevation view; and,

FIG. 5 is a right side elevation view thereof, the left side elevation view thereof is a mirror image of the right side elevation view.

In the drawings, the broken lines showing portions of a food grater depict environment and form no part of the claim.
